UNITED STATES PATENT OFFICE.

THOMAS H. LOVEJOY, OF CHICAGO, ILLINOIS.

PUNCH.

SPECIFICATION forming part of Letters Patent No. 770,239, dated September 13, 1904.

Original application filed September 28, 1903, Serial No. 174,261. Divided and this application filed May 5, 1904. Serial No. 206,458. (No model.)

To all whom it may concern:

Be it known that I, THOMAS H. LOVEJOY, a citizen of the United States, residing in Chicago, in the county of Cook and State of Illinois, have invented a new and useful Improvement in Punches, of which the following is a specification.

My invention relates to improvements in punches for punching holes in metal.

10 Metal-punches have heretofore generally been made in the form of a solid tool or punch which is secured to the stock by a threaded coupling or nut, a separate tool or punch being required for each different size of hole desired to be formed. This requires a very large number of punches or tools and also considerable expense, and if one of the punches or tools of a larger size happens to break, although the fracture may occur at its point or 15 smaller end, the whole tool is ruined and requires to be thrown away. Also in the larger sizes of solid punches difficulty is frequently experienced in properly hardening and tempering the tool without causing internal strain, 20 weakness, and liability to fracture.

25 The object of my invention is to provide a compound metal-punch so that the same punch may be used for punching holes of a plurality of different sizes and so that in case of breakage, which usually occurs at the smaller or pointed end of the punch, only a comparatively small and inexpensive piece of the hardened tempered tool-steel will be lost, thus effecting a very great saving of expense.

30 My invention consists in the means I employ to accomplish this result—that is to say, it consists, in connection with the punch-stock and threaded coupling or nut, of a hollow punch or punch-shell and a smaller solid punch fitting or nesting in the hollow punch or shell and a thrust-block fitting in the hollow punch or shell and interposed between the smaller solid punch and the punch-stock, so that the smaller solid punch will serve, in combination 35 with the hollow punch or shell, as the lower or pointed end thereof in making larger holes of the size of the shell and also serve as the

small punch in making holes of the size of the solid punch.

My invention further consists in the novel 50 construction of parts and devices and in the novel combinations of parts and devices herein shown and described.

As the punch-shell which is used in my invention in forming the larger-sized holes is 55 hollow, it will be readily understood that it can be easily hardened and tempered without danger or injury, and as in my invention any breakage of the punch-point only affects the small solid punch, which is a comparatively 60 small piece of tool-steel, it can be removed at little expense, and the punch-shells, which are the larger and more expensive pieces, are seldom liable to fracture.

65 In the accompanying drawings, forming a part of this specification, Figure 1 is a side elevation, partly in vertical section, of a punch embodying my invention. Fig. 2 is a central vertical section through the compound punch. Fig. 3 is a section on line 3 3 of Fig. 2, and 70 Fig. 4 is a detail perspective view of the small solid punch.

In said drawings, A represents the die, X, the plate of steel or other metal to be punched; A', the stripper-plate; B, the threaded coupling or nut, and C the stock to which the punch is secured by the coupling or nut and by which it is reciprocated or operated.

75 D is a hollow punch or punch-shell used for making larger-sized holes, and D' is a smaller 80 solid punch fitting and nesting in the hollow punch or shell D.

F is a thrust-block interposed between the smaller solid punch D' and the threaded stock C, the thrust-block F fitting in the hollow 85 punch or shell D and abutting at its lower end against the head d of the lower or solid punch D' and abutting at its upper end directly against the threaded stock C.

90 The head d of the solid punch D' has a conical or flaring exterior shoulder d', fitting the corresponding interior beveled shoulder d' of the hollow punch or shell D, and the head or upper end d' of the hollow punch or shell D has

a corresponding exterior beveled shoulder d^4 , fitting the corresponding interior beveled shoulder b of the coupling or nut B.

I claim—

5 1. In a punch, the combination with the punch-stock and threaded coupling or nut having an internal shoulder, of a hollow punch having an external shoulder or head engaging the internal shoulder of the coupling, and provided with an internal shoulder, and a smaller solid punch fitting and nesting in the hollow punch and having an external shoulder or head engaging the internal shoulder of the hollow punch, and a thrust-block fitting in 15 the hollow punch and abutting at one end against the stock and at its other end against the solid punch, substantially as specified.

2. The combination with a punch-stock and coupling, of a hollow punch connected to the punch-stock and coupling, and provided with an internal shoulder, of a smaller solid punch fitting and nesting in the hollow punch and provided with an external shoulder or head 20

engaging the internal shoulder of the hollow punch and a thrust-block fitting in the hollow punch and abutting at one end against the punch-stock, and at its other end against the smaller solid punch, substantially as specified. 25

3. The combination with a punch-stock C and threaded coupling B, having an internal bevel-shoulder b , of punch-shell D having an external bevel-shoulder d^4 engaging said internal bevel-shoulder b of the coupling, and provided with an internal bevel-shoulder d^2 , and punch D', fitting and nesting within said 30 punch-shell D, and having an external bevel-shoulder engaging the internal bevel-shoulder on the punch-shell, and a thrust-block F fitting within said punch-shell, and abutting at one end against the punch-stock and its other 35 end against said punch D', substantially as specified. 40

THOMAS H. LOVEJOY.
